DRILLING BIT

Thomas H. Stancilff, Houston, Tex., assignor to
 Reed Roller Bit Company, Houston, Tex., a
 corporation of Texas

Application January 30, 1939, Serial No. 253,563

2 Claims. (Cl. 255—71)

This invention relates to drilling bits, and particularly that type of drilling bit known as a roller bit, wherein the cutting action is produced by rollers which engage the formation with a rolling action and which have teeth thereon which dig into the formation as the rolling action takes place.

The general object of this invention is to provide such a drill bit in which the cutter teeth will be less apt to break off in use than those heretofore employed.

The present invention relates particularly to the formation of the teeth on roller cutters so located that in use there is an end thrust exerted through the teeth upon the cutters in the same direction substantially at all times. It has been customary in the past to form the teeth on these cutters in many instances in rows extending circumferentially with respect to the cutters. In some instances these rows are separate and in other instances they form continuous spirals. Customarily such teeth have been formed with their opposite sides disposed at equal angles to a line perpendicular to the axis of the rotation of the cutter. Thus, although the teeth were equally strong in both directions to resist a thrust action thereagainst, substantially all the thrust was in actual practice exerted in one direction.

It is an object of this invention, therefore, to so form the teeth on a roller cutter of the type set forth that the teeth will be better able to take the thrust stresses imposed upon it during operation.

In the drawing:

The single figure illustrates a vertical cross section with parts shown in elevation, however, illustrating a bit having thereon cutters constructed in accordance with this invention.

Referring more in detail to the drawing, the numeral 1 indicates the body of the bit and the numeral 2 the threaded shank whereby the bit is secured to the lower end of a drill stem. Mounted upon opposing downwardly extending arms 3 are a pair of side roller cutters 4, only one of which is shown, which are adapted to cut at the sides of the bottom of the hole. Extending between the inner ends of the spindles on which these cutters 4 are carried is a bridge 5, the central portion of which is formed with an opening for a purpose presently to be described.

Extending downwardly from opposed portions of the head and at positions intermediate the arms 3 are a pair of additional arms 6, these being in this instance joined to the head by

welding 7. Carried by the arms 6 either integrally or otherwise as desired are sections of cross roller pins 8 and 9, the inner ends of which are adapted to be positioned within the opening in the bridge 5 and welded therein as shown at 10. Intermediate the ends of these shafts races are provided thereon for the roller bearings 11 and 12 which are adapted to take the radial load on the cutters 13 and 14, and ball bearings 15 adapted to take the end thrust from these cutters. It will be noted that each of the thrust ball bearings 15 is positioned to take end thrust in a radially outward direction only, but this is sufficient because of the fact that this is the only substantial thrust which occurs during the operation of the bit.

It will be seen that while the bit is in operation due to the fact that the roller cutters 13 and 14 do not have a true rolling action on the bottom of the hole, there will constantly be a force exerted on the cutters through the teeth 16 and 17 thereof tending to move these cutters radially outwardly. This force likewise tends to break off these cutter teeth. In order to counteract this tendency and to make the teeth better able to resist the outward thrust action exerted upon them, this invention contemplates that the teeth shall have their opposite sides disposed at equal angles not with respect to a line perpendicular to the axis of the cutter, as in my prior Patent No. 1,998,793, dated April 23, 1935, but with respect to a line inclined toward the inner end of the cutter. In the particular instance illustrated, the opposite sides of the teeth are disposed at substantially equal angles with respect to a line normal to the cutting surface of the cutter. Because of the generally tapering formation of the cutter toward the center of the bit, this means that the teeth are generally speaking inclined toward the center of the bit rather than extending downwardly in a direction parallel to the axis of the bit. Furthermore, they extend substantially at right angles to the solid portion of the cutter on which they are carried. In the particular example illustrated, where the inclined angle between the inner and outer faces of each tooth is 36°, the inner face is disposed almost vertically, being only 6° from the vertical, while the outer face is at 30° from the vertical, thus serving to support the tooth against outward thrust.

It will readily be seen that by the construction set forth a cutter has been produced having teeth which will be better able to resist the end thrust imposed upon them during operation of the bit.

and which will thus stand up under heavier loads and over longer periods than cutters having teeth formed as was heretofore the practice.

Having described my invention, I claim:

- 5 1. In a drill bit, a body, a cross roller shaft extending transversely of and normal to the vertical axis of said body, roller cutters mounted on said shaft, said cutters having cutting teeth projecting therefrom and arranged in rows extending circumferentially with respect to said cutters, said teeth having opposite faces disposed at an angle to each other in such a manner that a plane passing through the apices of said circumferentially arranged teeth and normal to said transverse cross roller shaft will divide said teeth into two portions, one portion which is the major portion lying radially outwardly of said normal plane, and the other portion which is the minor portion lying radially inwardly of said
- 10 20 normal plane.

- 5 2. In a drill bit, a body, a cross roller shaft extending transversely of and normal to the vertical axis of said body, frusto-conical roller cutters rotatably mounted on said shaft with their smaller ends adjacent the vertical axis of said body, said cutters having cutting teeth projecting therefrom and arranged in rows extending circumferentially with respect to said cutters, said teeth having opposite faces disposed at an angle to each other in such a manner that a plane 10 passing through the apices of said circumferentially arranged teeth and normal to said transverse cross roller shaft will divide said teeth into two portions, one portion which is the major portion lying radially outwardly of said normal plane, and the other portion which is the minor portion lying radially inwardly of said normal plane.
